UNITED STATES PATENT OFFICE.

WALTER C. HADLEY, OF NEW YORK, N. Y., ASSIGNOR TO CENTRAL TALKING MACHINE SHOP, INC., OF NEW YORK, N. Y., A CORPORATION OF NEW YORK.

JUVENILE BLOCKS.

Application filed August 20, 1920. Serial No. 404,968.

To all whom it may concern:

Be it known that I, WALTER C. HADLEY, a citizen of the United States, and a resident of the city of New York, borough of Manhattan, in the county and State of New York, have invented new and useful Improvements in Juvenile Blocks, of which the following is a full, clear, and exact description.

10 The present invention relates to juvenile blocks, and more particularly to a set of blocks arranged to rest upon the projecting ends of the white keys of an automatic or self-playing piano, and having upon their 15 faces amusing pictures of humans and animals, to simulate dancing and jumping figures, said blocks being cubical in form; and also embodying spacing blocks to be interposed between the cubical blocks, all the 20 blocks being operated by the up and down movement of the white keys of the piano while playing a piece of music.

To the above ends, the present invention consists of a set of blocks comprising a plurality of cubical blocks with intermediate spacing blocks, the cubical blocks being along one line substantially the width of two white keys of a piano, and the intermediate spacing blocks substantially the width 30 of a single white key.

The invention is illustrated in the accompanying drawings, in which—

Figure 1 shows in front elevation a plurality of the blocks arranged in operative position upon the white keys of a piano, and illustrating the operation thereof;

Figure 2 shows a vertical cross-sectional view through a portion of the piano, and showing in side elevation a portion of one 40 of the black and one of the white keys of a piano, and also in side elevation one of the cubical blocks and one of the spacing blocks;

Figure 3 shows in perspective, one of the 45 cubical blocks;

Figure 4 shows in perspective one of the spacing blocks.

As shown in Figure 3, the cubical block 1 will have upon one or more of its faces, and 50 preferably each face, a picture of a figure, 2, which may be either dancing human figures, or as shown in Figure 1, animal figures. These blocks are made of any suitable light material, either light wood or cardboard. Each edge 3 of the blocks 1 will

preferably be substantially the width of two of the white piano keys 4. Co-operating with the blocks 1 are spacing blocks 5, which in vertical cross-section are substantially triangular in shape. The base of the triangle 6 is substantially the width of a white key 4. From the base 6, the sides of the block 5 converge on the inclined lines 7, meeting at the apex 8. Upon the triangular faces at the ends of the blocks 5, are shown figures 9, which may be either of humans or animals. In operation, the spacing blocks 5 are interposed between two cubical blocks as shown, in Figure 1, the spacing blocks 5 resting upon one of the white keys 4 of the piano, and the cubical blocks upon two immediately adjacent keys. Preferably, the length of the spacing blocks 5 and the lines 3 of the cubical blocks 1 will be substantially the length of the white keys 4 as they project beyond the black keys 10, whereby the black eyes form a positioning stop for the blocks, as is shown in Figure 2.

In operation, the blocks being positioned on the projecting ends of the white keys as 80 shown in Figure 1, as the white keys rise and fall the cubical blocks will tip sidewise, assuming that only one of the pair of keys upon which the block rests is moved, giving the impression of dancing figures. The 85 spacing blocks rise and fall with the white keys on which they are mounted.

Having described my invention, I claim as new:

1. A set of juvenile blocks comprising a 90 plurality of blocks provided with substantially rectangular faces, one face of which is substantially the width of two white keys of a piano, and a plurality of spacing blocks having inclined sides and a base substantially the width of a single white key of a piano, the spacing blocks being of less height than the other blocks, and all of said blocks bearing upon one face amusing pictures.

2. A set of juvenile blocks comprising a 100 plurality of cubical blocks each face of which is substantially the width of two white keys of a piano, and a plurality of spacing blocks having inclined sides and a base substantially the width of a single 105 white key of a piano, the spacing blocks being of less height than the cubical blocks and said blocks bearing upon their faces amusing pictures.

WALTER C. HADLEY.
